[57] CLAIM

The ornamental design for a bag dispenser, as shown and described.

DESCRIPTION

FIG. 1 is a perspective view of a bag dispenser showing my new design;

FIG. 2 is a front elevational view thereof;

FIG. 3 is a left side elevational view thereof; the right side being a mirror image of that shown;

FIG. 4 is a top plan view thereof;

FIG. 5 is a rear elevational view thereof;

FIG. 6 is a bottom plan view thereof; and

FIG. 7 is a perspective view of an alternative embodiment thereof, the only difference residing in the absence of the perforation pattern on the front surface.

FIG. 1

FIG. 2

FIG. 3

FIG. 4

FIG. 5

FIG. 6

FIG. 7
